CLAIM

The ornamental design for a tracheostomy plaster as shown and described.

DESCRIPTION

1. Tracheostomy plaster

1.1 : Left view illustrating a tracheostomy plaster;

1.2 : Right view of the tracheostomy plaster;

1.3 : Bottom view of the tracheostomy plaster;

1.4 : Top view of the tracheostomy plaster;

1.5 : Perspective view of the tracheostomy plaster;

1.6 : Back view of the tracheostomy plaster; and

1.7 : Front view of the tracheostomy plaster.

The broken lines shown in 1.6 illustrate portions of the tracheostomy plaster form no part of the claimed design.

1 Claim, 7 Drawing Sheets
